UNITED STATES PATENT OFFICE.

HUGO JUNKERS, OF DESSAU, GERMANY.

INTERNAL-COMBUSTION ENGINE.

Application filed April 9, 1927, Serial No. 182,323, and in Germany April 16, 1926.

My invention refers to internal combustion engines and has particular reference to engines provided with scavenging air or charging pumps, the piston of which is combined with the working piston of the engine. It is an object of my invention to improve this type of engine by shaping the scavenging air pump in a particular manner, whereby a number of important advantages are obtained.

The use of cylindrical pistons involves the disadvantage that a juxtaposition of two working cylinders is rendered difficult by the cross-section. On the other hand, if the space required for two adjoining pistons is of no avail, but it is desired for other reasons to make the pump piston large in diameter, for instance in order to be enabled to accommodate parts of the gearing within the cross-sectional area of the pump, it may happen that the cross-sectional area of the pump pistons becomes unduly large, so that the quantity of scavenging air delivered by the pump is excessive. Double piston engines in which the scavenging air piston is mounted on the outer working piston and the pistons are operated by means of connecting rods extending laterally of the cylinder involve the further disadvantage that in order to secure these pistons against angular displacement special means, such as guide ledges in the wall of the cylinder must be provided.

According to the present invention the cylindrical scavenging air piston and cylinder are replaced by a cylinder and piston of non-cylindrical cross-section, which is so chosen that both cylinder and piston can easily be made and centered.

To this end the piston of a scavenging air pump is given the sectional form of a sector of a cylinder cooperating with a pump cylinder of similar section.

I am aware that scavenging air pumps having a cylinder and piston of rectangular or elliptical cross-section have already been suggested, but in contradistinction to the present invention such cylinders and pistons cannot be manufactured without great difficulty and the centering of the parts is rendered very difficult.

The particular cross-section of the cylinder sector according to the present invention can be chosen in accordance with the particular conditions of each individual case.

In the drawings affixed to this specifica-

tion and forming part thereof several modifications of an engine embodying my invention are illustrated diagrammatically by way of example.

In the drawings

Figs. 1, 2, and 3 are cross-sections of three different forms of a cylinder and piston according to this invention.

Fig. 4 is a cross-section, drawn to a larger scale, and

Figs. 5 and 6 are axial cross-sections on the lines V—V and VI—VI, respectively, in Fig. 4, of a double piston engine according to the present invention.

In the pump shown in Fig. 1 the cylinder 30 has circular cross-section, while the piston 35 has the cross-section of a cylinder-sector bounded by two straight and two curved sides. The gaps between the pump piston and cylinder are filled by plane walls 31 resting on the inner wall of the cylinder 30 with their outer edges 32 and with extensions 33 mounted on their middle lines, and which are fixed to the cylinder wall by suitable means. In the covers (not shown) of the spaces confined between the walls 31 and the cylindrical cylinder wall 30 can be accommodated valves indicated at 37, and the free spaces 36 can be utilized for conveying or accommodating the medium, such as air, delivered by the pump. The walls 31 prevent any angular displacement of the piston.

In manufacturing a pump cylinder as shown in Fig. 1, I prefer proceeding as follows:

The intermediate walls 31 being finished on their innerside, are mounted in pairs on a pattern piston exactly corresponding to the pump piston 35, and the outer edges 32 as well as the free edges of the parts 33 are turned down to the exact diameter of the scavenging air cylinder. Now the pattern piston, together with the parts 31, 31 is mounted in the scavenging air cylinder, 100 which has first been turned down to the true diameter, and the parts 31, 33 are secured in place within the cylinder, whereupon the pattern piston is withdrawn. The inserts 31, 33 are now correctly centered within the cylinder.

The piston 35 shown in Fig. 1 may be replaced by pistons such as shown in Figs. 2 and 3 and having a bi-convex and a bi-concave cross-section, respectively.

In the engine illustrated in Figs. 4—6 the circular parts of the cylinder wall are mere-

ly retained at those points where they contact with similar parts of the piston, while for the rest the true configuration of the pump is not circular, but can have any desired cross-section. This involves the further advantage that all the space which is not required by the piston can be utilized for the accommodation of valves and for the conveying of the air. Thus the cylinder according to Fig. 4 has rectangular cross-section and the cylindrical surfaces 40 are produced on the lathe in a single operation, together with the centering edge 41 (Fig. 5) and the abutments 42, against which are applied angular extensions 43 of the plane walls 44 of the cylinder, screw bolts 45 serving for fixing the extensions 43 in position.

In the engine illustrated in Figs. 4-6 the two working pistons 50 and 51 are governed by the central connecting rod 52 and by lateral connecting rods 53 respectively, the three rods acting on a three-throw crank shaft 54. On the outer working piston 51 is mounted the scavenging air piston 55, a cross-head 56 serving for connecting the pistons to the outer ends of the lateral connecting rods 53, which are thus enclosed together with the cross-head in the cross-sectional area covered by the scavenging air piston 55. The working space of the scavenging air pump is accommodated between the pump cylinder cover 57 and the pump piston 55. The suction valves 58 are mounted in the cover 57 on both sides of the pump piston. As compared with the arrangement of these valves directly above the piston, I obtain the advantage that the end face of the piston can come quite close to the inner face of the cover, so that the valves do not act towards increasing the height of the engine. The pressure valves 59 are mounted in a plate 61 clamped between the cover 57 and the cylinder case 60 directly below the suction valves, so that the spaces 63, which are not utilized for the pump and are separated by the walls 44, can be utilized for the conveying of the air.

As shown in Fig. 6 these spaces 63 are in connection with the space below the scavenging air piston 55, so that also that part of the pump which is not utilized for the delivering of air may serve as receiver. While in former arrangements the pressure valves had to be accommodated in the piston, whereby the height of the engine was increased together with the weight of the piston, and the valve plates had to take up additional mass forces in consequence of the piston movement, I obtain the advantage that the valves are stationary and easily accessible, a large space being available for their accommodation. However, if it should prove desirable, the pressure valves can also be mounted at the piston itself.

In pumps according to the present invention the intermediate walls and other insertions which serve for reducing the original circular cross-section of the cylinder may be made of other material (for instance cast iron) than the pump case, which may for instance consist of light metal.

My invention is applicable to all kinds of internal combustion engines which require an auxiliary pump for gaseous material, independently from the particular construction of the engine (whether single or double piston), from the mode of operation (whether with artificial ignition or with ignition by compression), and from the fuel (oil, combustible mixtures of air and vapor or gas). The pumps according to the present invention may be made single or double acting and the original cross-section of the cylinder may also be of annular instead of full circular cross-section. Several pumps (for instance one for air and one for gas) may be combined with one working cylinder.

I wish it to be understood that I do not desire to be limited to the exact details of construction shown and described for obvious modifications will occur to a person skilled in the art.

I claim:

1. Internal combustion engine comprising a substantially cylindrical working cylinder and piston and a scavenging air pump piston, said pump piston having outwardly the form of a sector of a cylinder.

2. Internal combustion engine comprising a substantially cylindrical working cylinder and piston and a scavenging air pump piston fixed to said working piston, said pump piston having outwardly the form of a sector of a cylinder.

3. Internal combustion engine comprising a substantially cylindrical working cylinder and piston and a scavenging air pump cylinder and piston, said pump piston having outwardly the form of a sector of a cylinder, and filling pieces inserted in said pump cylinder.

4. Internal combustion engine comprising a substantially cylindrical working cylinder and piston and a scavenging air pump cylinder and piston, said pump piston having outwardly the form of a sector of a cylinder, filling pieces inserted in said pump cylinder and means for utilizing cavities in said filling pieces for the passage of the medium delivered by said pump.

5. Internal combustion engine comprising a substantially cylindrical working cylinder and piston and a scavenging air pump cylinder and piston, said pump piston having outwardly the form of a sector of a cylinder, said pump cylinder having a cross-section to match the form of said pump piston.

6. Internal combustion engine comprising a substantially cylindrical working cylinder

and piston and a scavenging air pump cylinder and piston, said pump piston having outwardly the form of a sector of a cylinder, said pump cylinder having a cross-section 5 to match the form of said pump piston, and a casing surrounding said pump cylinder.

7. Internal combustion engine comprising a substantially cylindrical working cylinder and piston and a scavenging air pump cylinder and piston, said pump piston having outwardly the form of a sector of a cylinder, said pump cylinder having a cross-section 10 to match the form of said pump piston, a casing surrounding said pump cylinder 15 and a valve in said casing outside said pump cylinder.

8. Internal combustion engine comprising a substantially cylindrical working cylinder and piston and a scavenging air pump cylinder and piston, said pump piston having 20

outwardly the form of a symmetrical cylinder sector, said pump cylinder having a cross-section to match the form of said cylinder, a quadrangular casing surrounding and spaced from said cylinder and bracing 25 means connecting the walls of said casing and said cylinder.

9. Method of making a scavenging air pump as claimed in claim 3, comprising mounting two filling pieces on the non-cylindrical faces of a pattern piston having the form of the pump piston, reducing the outer surface of the combined pattern and filling pieces to the exact cross-section of the pump cylinder, introducing the combined 30 parts in said cylinder, securing said filling pieces in position in said cylinder and withdrawing said pattern.

In testimony whereof I affix my signature.
HUGO JUNKERS.
